REFRIGERATOR DOOR LATCH

George E. Curtiss, Jr., Penn Wynne, Pa., assignor to Philco Corporation, Philadelphia, Pa., a corporation of Pennsylvania

Application May 25, 1948, Serial No. 28,987

4 Claims. (Cl. 292—332)

1

This invention relates to latches of the type commonly used on refrigerator doors.

More particularly, the invention relates to an improved latch of the general type disclosed in my Patent No. 2,445,709, issued July 20, 1948, that is, a latch mechanism in which a progressively increasing latching force is exerted by the bolt as it approaches its fully latched position, with the maximum available force being applied at the time when the bolt member is fully "home," and the door is completely closed. As set forth in said co-pending application, the mechanism results in an unusually high degree of "draw in" coupled with absolute prevention of rebound.

The aforesaid latch is constructed in a manner providing a self-cocking feature whereby the bolt may be held in a retracted position ready to snap to an advanced operative position engaging the associated keeper, when the refrigerator door is swung closed. However, the bolt is subject to accidental tripping from this position, and may move to the advanced latching position, while the door is still open. When in the latter position, and the door is swung to closed position, one of the particular advantages of the mechanism is that the bolt is first urged into a retracted position from which it then moves into latching engagement with said keeper. Thus, the bolt will move into latching engagement with the keeper whether the latch is in retracted or in advanced position, when the door is swung from open to closed position.

In the aforesaid latching mechanism it has been found necessary, when the uncocked bolt is moved toward latching engagement with the keeper, to overcome a restraining force exerted by certain parts of the mechanism. This force was overcome by applying a greater force to the door when closing it. In general, it was highly desirable to solve this problem in such a way as to reduce, insofar as possible, the force required to close the door under the abnormal condition above-noted and, in seeking such a solution, the present invention was conceived.

The invention has, therefore, as its primary object, the provision of an improved latch mechanism of the aforesaid type.

More particularly, it is an object of the invention to provide a latch mechanism characterized by its relative ease of operation and its prompt actuation to fully latched position, regardless of the position of the bolt when the door is swung closed.

These and other objects of the invention, here-

2

inafter appearing, will be more readily understood by reference to the several views of the accompanying drawings, in which:

Figure 1 is a perspective view of a refrigerator embodying the present invention;

Figure 2 is a sectional view, on an enlarged scale, taken along the plane indicated by line 2—2, of Figure 1, the latch mechanism being shown in its fully latched position;

Figure 3 is a view similar to Figure 2, but on a smaller scale, and showing the mechanism in its normal unlatched and retracted condition, that is, with the bolt cocked, the door being shown in a position just prior to reaching its fully closed and latched condition;

Figure 4 is a view essentially similar to Figure 3, but illustrating the bolt in its uncocked position; and

Figure 5 is a sectional view on an enlarged scale, taken along the plan indicated by line 5—5 of Figure 1, the latch mechanism being shown in fully latched position.

Referring now to the drawings and more particularly to Figures 1 and 2, the numeral 10 designates a refrigerator comprising a cabinet 11 having a door 12. As seen in Figures 2 and 5 the door comprises an inner panel 13 and an outer panel 14 joined about their peripheries at 15 (Figure 5) as by screws 17, which serve also to fasten the customary resilient sealing gasket 18 to the door, at that juncture. Gasket 18 is adapted to impinge against the door jamb 19 of the cabinet and thereby provide an airtight seal between the door and cabinet, when the door is closed. Mounted adjustably on the door jamb (Figure 2) is a keeper 20 which is provided with a strike 22 having a cam face 23, the purpose of which will be explained hereinafter.

As more clearly shown in Figure 5 of the drawings, the latch includes a support or housing 24 having a bottom wall 25 and a pair of parallel side walls 26 and 27. The inner end of side wall 26 is provided with a flange 28 through the agency of which the housing is secured to junction 15 of the inner and outer door panels, as by one of the aforesaid screws 17. Housing 24 may be formed in any convenient manner, but it has been found desirable to fabricate it by welding the separate elements forming side walls 26 and 27 and bottom wall 25. The bottom wall is secured by screws 29 to the peripheral flange 30 of a support member 31 welded, or otherwise suitably attached, to the outer door panel 14. With reference to Figure 2, it is seen that a portion 35 of wall 25 extends upwardly beyond flange

30 of member 31. This extension is provided with inwardly turned ear portions 36 in which the ends of a pivot pin 37 are fixed. Pin 37 extends through a slot 38 in an elongated latch bolt 39, which latter is adapted for movement about said pin into and out of latching engagement with keeper 20 as hereinafter described.

5 Latch bolt 39 comprises a depending arm portion 40 which terminates at its lower end in a pair of spaced finger portions 41 and 42. Finger 42 provides the keeper-engaging portion of the latch bolt, engagement being facilitated by a pair of rollers 43, one being provided on each side of its tip (see Figure 5). Finger 41 is the trigger for moving the bolt from its retracted position, 15 shown in Figure 3, into extended position engaging the keeper, as is more fully described herein-after. The force utilized to move the bolt into extended position is provided by a strong spring 44 positioned on arm 40, with one end impinging against shoulders 45 of the link and its other end adapted to react against pin 37.

Movement of the bolt between extended and retracted positions, when moving in its normal mode of operation, is guided by a pair of links 46. 20 Each of the links is pivotally mounted at one end on a pin 47, the ends of the latter being secured in side walls 26 and 27 of the housing, while the portion intermediate the ends of the pin passes between the fingers 41 and 42 of the bolt.

A particular feature of the invention, as more fully described hereinafter, resides in the manner in which the other or free ends of the links engage the latching member to guide it in its normal latching movements, yet still permit free relative movement between said links and member during abnormal latching movement. This engagement takes place through a pin 48 which connects the free ends of the links and has its intermediate portion engaged in a slot 49 formed in the portion of the bolt which bridges the space between fingers 41 and 42.

Still with reference to Figures 2 and 5, it is seen that the left-hand end of pin 48 is provided with a roller 50 positioned in the path of movement of an inwardly extending finger 51 of handle 52. The handle is pivotally mounted on a channel-shaped member 54 welded or otherwise secured, as indicated at 55, to bottom wall 25 of housing 24. The handle is normally biased toward its rest position, as shown in Figure 2, by a spring 56.

The operation of the latch is as follows:

As viewed in Figure 2, roller 43 is in latching position behind the strike 22 of keeper 20. When it is desired to open the door the handle 52 is grasped and rotated in a counterclockwise direction about its pivot 53. This movement urges the contacting surface 51a of handle extension 51 against roller 50 on pin 48, thus rotating the links in a clockwise direction about their pivot 47.

Rotation of these links, as described, moves latching member 39, against the pressure of spring 44, in a direction determined by the arcuate movement of pin 48 about pin 47—as guided by engagement of pin 48 in slot 49—and to an extent withdrawing roller 43 from behind keeper 20, as seen in Figure 3, thereby permitting the door to be swung open. This movement of latching member 39 continues until an extension 58 of one side edge of slot 49 contacts pin 47, at which position, as indicated in Figure 3, pin 48 has moved to or preferably slightly past a position of dead center with respect to pin 47 and the line of thrust of spring 44 against pin 37. As illustrated in Figure 3 this dead center position is reached when the

straight line between pins 37 and 48 corresponds to a straight line 57 intersecting the axis of pins 37 and 47. Release of handle 52 by the operator permits spring 56 to return the handle to its normal position as illustrated in Figure 2, while the latch remains in its retracted or cocked position.

To close and latch the door the latter is merely swung toward closed position until trigger finger 41 strikes the forward edge 22a of strike 22 (Fig. 3) which causes the latching member to move to the left, shifting pin 48 back past the aforesaid dead center position, so that the thrust of spring 44 may operate to urge the mechanism toward latched position. At the instant pin 48 passes the line of dead center (57), it is urged by the pressure of the spring 44 to move in a counter-clockwise direction toward the position illustrated in Fig. 2. This movement causes the latching member 39 to move downwardly, and to the left as viewed in Figure 2, guided by links 46 and pin 37, bringing roller 43 into contact with the keeper prior to completion of the link movement. Continued movement of the link draws the door forcibly into its fully closed position.

It is to be understood that, as the latching member approaches the fully latched position, the lateral component of movement of said member, that is, the component introduced by the strut-like action of links 46, becomes progressively smaller. Since, in a lever system of the kind here involved, the product of the input force and the distance through which the force is acting is always equal to the product of the output force and the distance through which the latter is acting, it will be evident that the aforesaid diminution of lateral movement is accompanied by a corresponding progressive increase in the lateral, or draw-in, force.

To a small degree, this increase in force is offset by a progressive decrease in the thrust of spring 44, but this is a minor factor.

Movement of the latching member in its downward or counter-clockwise direction is terminated when the upper end of slot 38 contacts pin 37, as indicated at 37a in Fig. 2, in which position pins 47 and 48 are in line with respect to the forces exerted against roller 43 so that rebound forces against the roller are exerted in a straight line against pin 47 and are thereby restrained.

Normal operation of the latch mechanism is as described above. However, when the mechanism is in the position illustrated in Fig. 3 and the door is opened to an extent permitting access to the refrigerator food storage compartment, it may readily be seen that the roller end of the bolt projects outwardly of the door structure in a position exposed to inadvertent actuation by forces great enough to move pin 48 over the dead center position, as described above. Such inadvertent actuation permits spring 44 to move the bolt to its latched position, while the door is still open.

In accordance with the foregoing statements of object and advantage, and as set forth in detail in what follows, the apparatus of the invention is such that the door may be moved to fully latched position even if the bolt or latching member be uncocked when the door is swung closed, the invention being particularly characterized in that latching of the door, under such conditions, may be accomplished with considerably less closing force than was required with related mechanisms available heretofore. This fea-

ture may best be understood with reference to Figure 4.

When the door is swung toward closed position—following inadvertent uncocking of the latch mechanism—roller 43 makes contact with cam face 23 of the strike 20, rolls upwardly along said face and thus forces the latch bolt 39 upwardly against the pressure of spring 44. This upward movement of the bolt or latching member takes place in a substantially straight line path determined both by pin 37 and slot 38, and by contact of the left hand edge 39a of bolt 39 against a guide member 26a fixed to side wall 26 of housing 24. The upward movement is of extent sufficient to permit the spring to move the roller 43 behind and into latching engagement with the keeper, as the door continues its closing movement. It is to be noted that the strike face 23 is provided with a sloped portion 23a, in order to facilitate entry of the roller 43 into latching position behind said strike.

Under the abnormal mode of operation just described, the upward movement of bolt or member 39 is independent of and relative to links 46 and said links are therefore not operative, as the roller 43 moves behind the keeper, to provide the lateral, or draw-in force, described above. Hence, under such condition of operation, the force applied to the door to effect closure thereof must be sufficient both to raise the bolt 39 against the pressure of spring 44 and to provide compression of the door gasket. Accordingly it is of major importance that the total force which must be exerted against the door be kept as small as possible. In the apparatus of the present invention, substantially all of the force exerted by the roller 43 against the inclined face 23 of the strike 20 is available to effect the necessary raising of the latch bolt.

To this end, and in contradistinction to related mechanisms heretofore available, the bolt is free to move with respect to the links 46, and it is therefore not necessary to overcome the restraining force which is present when the links 46 are pivotally secured to the latch bolt. Further, in the mechanism disclosed and claimed herein, the path of upward movement of the latch bolt is in general alignment with the direction of thrust reaction from the strike surface, thereby making such reaction fully effective in raising the latch bolt.

In the apparatus of the present invention, and as will now be evident, the latch bolt retracts through an unrestricted, substantially straight-line path aligned with the direction of thrust reaction from the strike surface and, therefore, retraction of the latch bolt is effected only against the force of spring 44, and such friction as exists in the mechanism. The spring, when thus loaded, then operates to move the bolt into latching engagement with the keeper, in the manner described.

From the foregoing, it will be understood that the invention herein disclosed and claimed provides apparatus which not only realizes the positive action and secure draw-in required for proper latching of large and heavy doors presently in commercial use but, further, is of such a nature as to effect an important reduction in the force which must be applied to the door to effect closure thereof when the latch bolt has been inadvertently tripped and moved to uncocked position.

I claim:

1. In a door latch, the combination with support structure of an elongated latch member adapted for interlocking engagement at one end with a keeper, means mounting the latch member for simultaneous oscillatory and longitudinal movement with respect to said structure, and means to control the oscillatory and longitudinal movements of said latch member so as to cause said latch member to move between a retracted position with respect to the keeper and an extended position in which said latch member is in interlocking engagement with the keeper, said control means comprising a spring exerting force tending to advance the latch member into the said extended position, and means guiding the movement of said latch member, said guide means comprising an element having a portion adapted to react against said support structure, and another portion—spaced from the first mentioned portion—normally engaging said latch member in a manner to effect arcuate movement of the latch member from said retracted position to said extended position with progressively amplified force under the influence of said spring, the engagement between said element and said latch member further being such as to permit substantially straight line movement of said latch member independently of said element, said straight line movement being from extended position out of latching engagement with said keeper to extended position in latching engagement with said keeper, and said guide means further including fixed structure guiding said latch member in said straight line movement.
2. A door latch according to claim 1 wherein said guide element comprises a lever having one end thereof pivotally mounted for movement about an axis on said structure, and its other end releasably engaging said latch member adjacent its keeper-engaging end.
3. A door latch in accordance with claim 2 wherein the releasable engagement of said lever with said latch member is effected through a pin on said lever and a slot in the keeper-engaging end of said latch member, said pin normally passing through said slot.
4. A latch in accordance with claim 3 wherein in the latch member, the guide means, and the mounting means are so related with respect to each other that when the latch member is in retracted position, the point of engagement of said lever with said latch member will lie to one side of and closely adjacent to a straight line drawn between said axis and said mounting means, and when in extended position the point will lie at the other side of and relatively remote to said line, and wherein said latch additionally includes stop means for stabilizing the member in said positions.
